UNITED STATES PATENT OFFICE.

JAMES I. HIETT, OF ROCKMART, GEORGIA.

COMBINED COMB AND BRUSH.

1,102,919.

Specification of Letters Patent. Patented July 7, 1914.

Application filed November 17, 1911, Serial No. 660,835. Renewed December 10, 1913. Serial No. 805,860.

To all whom it may concern:

Be it known that I, JAMES I. HIETT, citizen of the United States, residing at Rockmart, in the county of Polk and State of Georgia, have invented certain new and useful Improvements in Combined Combs and Brushes, of which the following is a specification.

This invention has for its primary object 10 a simple, durable and efficient construction of brush and comb combined, the parts being so arranged that the comb of the device is normally held retracted by a spring, in the bristles, and being capable of being readily 15 moved out from the bristles to an operative position, by pressing a thumb piece or finger piece carried by the handle.

The invention has for a further object, a combination comb and brush in which the 20 parts are so constructed and arranged that an automatic movement of the comb into the brush will have a tendency to clean the teeth of the comb, the bristles serving to strip the teeth of hair or the like which will be left 25 on the working ends of the bristles where it may be easily removed. And the invention also aims to generally improve this class of devices and to render them more useful and commercially desirable.

With these and other objects in view, as 30 will more fully appear as the description proceeds, the invention consists in certain constructions and arrangements of the parts that I shall hereinafter fully describe and 35 claim.

For a full understanding of the invention, reference is to be had to the following description and accompanying drawings, in which:

Figure 1 is a side elevation of one form 40 or embodiment of my improved combination comb and brush; parts being shown in section; Fig. 2 is a substantially similar view, the parts being in different positions from 45 those illustrated in Fig. 1; Fig. 3 is a transverse section on the line 3—3 of Fig. 2.

Corresponding and like parts are designated by the same characters of reference throughout the several views in which they 50 appear.

It is to be understood that my invention is equally applicable for toilet or household use, and stable use, that embodiment of the invention illustrated in Fig. 1 being designed particularly for toilet use. Referring 55 to this view of the drawings, the nu-

meral 1 designates the back of a toilet brush and 2 the bristles thereof, the back and its bristles being of any desired construction and design, except that the back 1 is formed, 60 preferably along its median line, with a longitudinal slot 3, which preferably opens at the forward or free end of the back, and which is designed to receive a comb 4. Any construction or design of comb may be used, 65 and preferably, it is formed at its rear or body edge with a bead 5, as is often the case with combs of conventional type, the bead being adapted to be slipped into a slotted tube 6 which is formed at one end with a shank 7 and a collar 8 contiguous to said shank, the shank being connected to a preferably tubular standard 9 telescopically mounted in a tubular bushing 10, which is secured within the hollow post 11 of a 70 handle 12, secured to the rear face of the back 1 at one end thereof, as clearly illustrated in the drawings. Preferably, the outer end of the tube 6 is connected to one end of the standard 9 by an obliquely extending brace 13.

Mounted within the bushed post 11 and the tubular standard 9 is an expansion spring 14, said spring at one end engaging the standard 9 as by bearing against the adjoining end of the brace 13 which projects into the standard, and the other end of said spring then encircling and being positioned around a rod 15 which is secured to the back within the post 11. As is manifest, the 85 tendency of the spring is exerted upon the parts to move the tubular standard 9 outwardly from the bushing 10, whereby the comb 4 will be retracted in the bristles and automatically moved to an inoperative position. If desired, the post 11 may be capped by a thumb or finger piece 16.

From as much of the description as has preceded, in connection with the accompanying drawings, the operation of my improved combination brush and comb will be apparent.

In the practical use of the device, when it is used as a brush only, the spring 14 will be permitted to act so as to hold the comb in a retracted position. Whenever it is desired to use the comb, it is only necessary for the operator to press his or her thumb or finger on the end of the tubular standard 9, whereupon the spring will yield and the comb 110 may be easily moved to an operative position, with its teeth projecting from the

working ends of the bristles 2. When the pressure on the thumb or finger piece 16 has been removed, the spring 14 will again be permitted to act to retract the comb, and in this 5 retracting movement it is clear that the bristles will wipe the opposite sides of the teeth of the comb and tend to remove therefrom hair or the like which otherwise might cling thereto.

10 It will thus be seen that I have provided a very simple and efficient comb and brush, the parts of which may be easily constructed and readily assembled.

15 It is to be particularly noted that the comb 4 may be easily detached from the tubular comb holder or tube 6, and be replaced by another should any of the comb teeth become broken or the comb become otherwise unfit for use.

Having thus described my invention, what 20 I claim is:

As an article of manufacture, a brush the back of which is formed with a longitudinal slot open at one end, a slotted tube, a comb 25 detachably mounted in said tube and projecting through the slot in the brush back, a hollow post mounted upon the brush back, a standard slidably mounted upon said post and carrying said tube, and a spring mounted in the post and bearing against the 30 standard.

In testimony whereof I affix my signature in presence of two witnesses.

JAMES I. HIETT. [L. S.]
